UNITED STATES PATENT OFFICE.

HENRY WATERMAN, OF NEW YORK, N. Y.

IMPROVEMENT IN STEAM-ENGINES.

Specification forming part of Letters Patent No. 40,656, dated November 17, 1863.

To all whom it may concern:

Be it known that I, HENRY WATERMAN, of the city, county, and State of New York, have invented a certain new and useful Improvement in Steam-Engines; and I do hereby declare that the following is a full, clear, and exact description thereof, reference being had to the accompanying drawings, making part of this specification, in which—

Figure 1 is a longitudinal transverse section of a steam-engine cylinder with my invention applied. Fig. 2 is a longitudinal transverse section of the heater lining the cylinder, with its internal plates removed. Fig. 3 is a plan of the heater lining the cylinder; Fig. 4, a transverse section, and Fig. 5 an end view, of Fig. 3. Fig. 6 is a plan of the heater resting upon the upper or front head of the cylinder, with one of its plates removed; and Fig. 7 is a plan of the heater resting upon the lower or back head of the cylinder, with a plate removed. Fig. 8 is a transverse section of the cylinder through the exhaust-nozzle. Figs. 9 and 10 are sections of the longitudinal bars and ribs, forming the frame of the heater lining the cylinder.

The same letters indicate like parts in all the figures.

I have, at considerable cost of time and labor and money, constructed a purely experimental condensing steam-engine, with boiler and appendages attached, and have made long and careful experiments therewith, which has led me to the discovery—

First. That in all condensing steam-engines, according to size, there is obtained only from one-half to one-quarter the dynamic effect due to the water which disappears from the boiler in the form of steam, and that this loss is principally due to condensation by external radiation in the first instance, even with cylinders and steam-pipes well protected by non-conducting substances.

Second. In consequence of the abstraction of heat from the metal composing the cylinder and its parts, a portion of the steam entering it is condensed to supply the deficiency, and as soon as the pressure in it is from any cause reduced, this condensed steam begins to re-evaporate, thus causing further loss by supplying the latent for it.

Third. That with cylinders steam-jacketed a great loss takes place when the whole cyl-

inder with all its connected parts is surrounded with steam of the same temperature as that used in the cylinder, and when so surrounded only one-sixth part of the value due to the expansion can be made available in consequence of the heat lost from the cylinder by the re-evaporation of water adhering to its interior surfaces, and by the vapor of the condensed steam being in contact with them, for, as the interior portion of the cylinder is during half the time exposed to the vapor of the condenser, which is of low temperature and pressure, it follows that heat will be absorbed from the hotter metal by the cooler vapor, and that, if water be present, the evaporation thereby produced will be rapid in accordance with such pressure, and will absorb a large quantity of heat from the innermost portion of the metal of which the cylinder is composed. In addition to the waste of heat thus occasioned, there is also another loss caused by the back-pressure which the vapor so generated exerts against the piston.

Fourth. That superheated steam does not contain heat in sufficient quantity to supply that lost by the condensation and re-evaporation when used at a temperature sufficiently low to prevent the abrasion of the metal composing the cylinder, piston, and valves.

In order to give practical effect to my invention, and as a means of obtaining nearly the full effect of the elastic pressure of the steam, it consists in combining with the engine internal heaters within the cylinder at each end and around its sides when it is double-acting, and at one end when it is single acting, which said heaters, or equivalent, consists of thin metal steam-tight vessels, of sufficient strength to contain steam of greater temperature than the steam used in the engine. By this means, owing to the thinness of the metal and the high temperature of the steam in contact with it, condensation is mostly prevented, and such condensed steam as may accumulate is re-evaporated as soon as brought within the influence of the heaters, by heat supplied from another source than the steam entering the cylinder, and the full dynamic power of the steam is maintained on the piston during its stroke, at small cost of heat supplied through heaters, compared to the great loss which would take place by reason of cooling down

the metal of the cylinder and piston in supplying the heat of evaporation. For if the heat be maintained in the metal of the cylinder and its parts at a temperature equal to the boiling-points due to the initial pressure of the steam entering them, condensation cannot take place, except by radiation and conduction to a cooler body; and when the cylinder and its parts are steam-jacketed, the only cool body in connection is the vapor in the cylinder in communication with the condenser, and what condensation takes place is caused by this effect alone.

And my invention also consists in increasing the power of and the economy of the engine by preventing condensation, in providing the means in these heaters, or equivalent, of supplying heat from another source than that in the metal of the cylinder and the steam entering it, to evaporate any water that may be present at the commencement of the stroke of the piston while it is close to the heater upon the cylinder-head, thereby arresting further condensation and preventing re-evaporation during nearly the whole stroke. For, as the vapor of such re-evaporation, if continued during the whole stroke, causes a resistance on the back side of the piston, which must be balanced by as much of the entering steam on the other side as its equivalent of pressure before any useful effect can be produced, and as re-evaporation takes place rapidly under the great reduction of pressure during the exhaust stroke, or on the condenser side of the piston; and as the greater the amount of water the greater will be the re-evaporation, and consequently the greater will be the back-pressure. It is therefore evident that any means that will reduce the amount of condensation, and will re-evaporate such as may accumulate at the commencement of the stroke without using the heat in the metal of the cylinder and its parts, or in the steam entering it; must result in increasing the power of the engine. I aver that this result cannot be obtained by any known means, except by my invention, for the reason that condensation and re-evaporation must inevitably take place, that more than three-fourths of it takes place at the commencement of the stroke, and by my invention is there evaporated without reducing the temperature of the metal composing the cylinder and piston, thereby nearly annihilating the injurious effects of re-evaporation in the cylinder by the application of heat from another source at the commencement of the stroke.

In the accompanying drawings, A represents the cylinder of a steam-engine, of any suitable construction, and B the side pipes and steam-chests containing valves of any suitable construction, and which I deem, therefore, unnecessary to describe. All these parts I prefer to have steam-jacketed by steam from the boiler supplying steam to the engine. I also prefer to separate the condensed steam formed in the steam-pipe, together with any priming.

water that may pass over with the steam from the boiler into a chamber in the pipe, before it enters the valve-chest, to be there drawn off and pumped back in the boiler. At each end of the interior portion of the cylinder, resting against its heads, are heaters c, whose sides are made of steel-plate one-tenth of an inch thick. Between these plates is interposed a ring of soft iron, b, one inch and a quarter thick, of equal external diameter with the bore of the cylinder, and of two and a half inches less internal diameter. The steel-plates are riveted to the ring by the rivets d, Figs. 6 and 7, which are three-eighths of an inch in diameter, placed one and a quarter inches apart. The edges of the plates are then calked, in the same manner as the edges of boiler-plates are in steam-boilers, thus making a steam-tight hollow disk of the same diameter as the bore of the cylinder.

For the purpose of increasing its strength, screw-braces e, three-eighths of an inch in diameter, are inserted through from one plate to the other. They are placed one and a quarter inches apart over the plane surfaces represented by the small cross-lines in Figs. 6 and 7, and their ends are riveted in the same manner as steam-boiler screw-braces. This hollow disk I term an "internal heater," to be placed on the lower or back head of the cylinder, and one, with a small ring interposed between the plates at the center to make an opening p for the piston-rod w to pass through it, is placed on the upper or front head of the cylinder. Before the rings are riveted between the plates, two holes, g, are drilled into them from the inner edge to within three-eighths of an inch of the outer edge, each one-half an inch in diameter, and the pipes h and h', passing through the heads, are screwed in through the plates into the side of the ring to the drilled holes, thus making communication to the internal part of the heaters. The pipes h are to communicate with the steam-chamber of a small auxiliary boiler, made sufficiently strong to sustain a pressure equal to 100° Fahrenheit's scale above the steam entering the cylinder at the commencement of the stroke, and the pipes h' are to communicate with the water in the lower part of the auxiliary boiler, provided the surface of the water in said boiler is lower than the pipes at h'. If the auxiliary boiler cannot be placed sufficiently below the pipes h', then they will be connected to a closed vessel having a force-pump attached to it, and the condensed steam flowing into it from the heaters by these pipes will be pumped into the said boiler. Around the internal sides of the cylinder is placed a heater, x, made of plate steel of the same thickness as the end heaters. They have four longitudinal bars, z, and three ribs, y, Fig. 2, interposed between the plates to form the steam-space and frame to rivet them to. The longitudinal bars are two and three-quarter inches wide and one and a quarter inches thick, with a feather in the center of the two widest

sides, projecting three-sixteenths of an inch above their faces, (the use of these feathers will appear hereinafter), on the ends, and in the middle of the bars on each edge are projecting arms m , Fig. 10, one and a quarter inches square, of sufficient length to form when curved to a segment of a circle, one-quarter of it. These arms form the interposing ribs y , and these, together with the bars, form the space between the plates, which are riveted to them through and through, the edges of the plates being calked to make them steam-tight. It being impracticable to calk the longitudinal seams of the plates composing the internal surface of this cylindrical heater in the ordinary way, and have a perfect surface on the internal side, the feathers c' are provided to overcome the difficulty. They are not needed for this purpose on the external side, but being a convenient and effectual method of calking are used for it also. These feathers are planed true and parallel, as well as the faces the plates are to be riveted to, the faces and ribs being curved to the circle required for any size cylinder. The longitudinal edges of the plates are planed, beveling to an angle of seventy degrees, as seen at c' , Fig. 4, and after the plates are riveted to the ribs and bars, the feathers are upset over the beveled edges, thereby forming perfect calked seams. The feathers are then dressed down to the curves, forming true and smooth surfaces. The end ribs have offsets in them, which form three sides of the steam-ports j through the heater. The dotted lines in Figs. 1 and 3 represent the offsets covered by the plate-steel. The heaters c form the fourth side of the ports. The plates are countersunk for all the rivets, and the rivet-heads are all dressed off smooth, with the curved surfaces on both sides. The middle rib and longitudinal bars have communicating holes drilled through them. (Shown by dotted lines at l , in Figs. 2 and 4.) The steam and condensed steam pipes h and h' pass through the side of the cylinder, and communicate with the drilled holes by being screwed into the middle rib at t , and these pipes lead to the boiler and closed vessel heretofore described. Screw-braces e' , three-eighths of an inch in diameter, are inserted through from one plate to the other, and are placed one and a quarter inches apart over all the intervening parts between the riveting. They are screwed in with red-lead paint, and their ends dressed off even with the curved surfaces. The joints t' are to be made tight with red-lead putty in the usual way. That part of them on one side of the ports at u will be made tight by two followers, k , curved to the bore of the cylinder, whose inner ends are beveled to an angle of one hundred and thirty degrees, lying against two pieces, v , beveled to match the followers k , the opposite ends of the four pieces forming right angles. Set-bolts s force the pieces k against those v which have putty under them, and the inclined planes carrying them down on the edge

of the heater c , thus making this part of the joint. The joints around the ports between the cylinder and the cylindrical heater at o are made by driving in hemp saturated with paint.

From the foregoing it will be seen that as the steam from the pipe h heats the thin metal of the heaters to a temperature greater than the steam entering the cylinder, any condensed steam or water that may be present will receive heat of greater temperature than that due to its pressure, and will be evaporated with a rapidity in accordance with the surface and difference of temperature between the heaters and entering steam, and that the heat required for the evaporation will be supplied by the heaters by contact, conduction, and radiation.

Instead of employing steam to supply heat to the heaters, it may be supplied by currents of heated air or heated gases passing through them; but I prefer steam for the purpose.

Instead of making the heaters separate and distinct vessels, they may be made in combination with the cylinder and heads by using only the thin metal plates next to the interior surfaces, or by constructing the cylinder and heads cellular, or by longitudinal or concentric spaces, leaving part of the metal forming the interior surfaces of the cylinder thin at the bottom of the cells or spaces. I prefer to employ steel for the interior surfaces of the cylinder, as in my judgment thinner surfaces of metal may be presented to the bodies to be heated made of steel than any other metal, but other metals may be used with proportionate good results, corresponding to thickness and temperature employed.

Instead of employing all the heaters, only a part of them may be employed—for instance, the heaters connected with the cylinder-heads may be only employed, or a heater may be used in one end of the cylinder of a single-acting engine, or a heater may be employed in one end and one around the sides of the cylinder.

I depend mostly on the heaters applied to the heads of the cylinder to effect the result to be attained by my invention, but do not limit myself to any particular way they may be employed when they are applied to the interior surfaces of steam-engine cylinders.

I am aware that steam-engines have been steam-jacketed (cylinders, heads, side pipes, and valve-chests) to prevent radiation and consequent condensation; but heaters have not been applied to the internal surfaces of the cylinder, and steam-jacketing will not answer the purpose contemplated by me. I am likewise aware that attempts have been made, but never with success, to prevent condensation in the cylinder by superheated steam. I therefore disclaim such modes. They are inefficient, and will not supply heat with sufficient rapidity nor in sufficient quantity to re-evaporate the condensed steam at the proper time.

One merit of my invention is, that it obtains the maximum efficiency heretofore aimed

at, but not realized, by such superheating contrivances. Another merit of my invention is, that it reduces the pressure on the back of the piston to its normal quantity, or only slightly more than is due to the temperature of the condenser, and only one-third the pressure that now takes place in steam-engines. And another merit of my invention is, that for equal horse-power developed in engines there will only be required from one-half to one-quarter the injection water needed than with the usual manner of using steam in engines; therefore, the steam-engine can be as efficiently worked with an air-pump and condenser of less proportional capacity and with surface-condensers of proportionally less surface.

I have discovered that re-evaporation or condensed steam in the cylinders of steam-engines is the principal cause of their inefficiency to realize the value of the expanding steam after it is cut off in the cylinder.

What I claim as my invention, and desire to secure by Letters Patent, is—

The method, substantially as herein described, of constructing the interior surfaces of the cylinders of steam-engines, in whole or in part, of as thin metal as will retain the pressure of the steam used, as set forth, and for the purposes specified.

HENRY WATERMAN.
